UNITED STATES PATENT OFFICE.

AUGUST W. KURZ, OF CLEVELAND, OHIO, ASSIGNOR TO WILLIAM B. WHITE, OF CLEVELAND, OHIO.

CATCH-BASIN RECEIVING-HEAD.

SPECIFICATION forming part of Letters Patent No. 774,846, dated November 15, 1904.

Application filed April 25, 1903. Serial No. 154,211. (No model.)

To all whom it may concern:

Be it known that I, AUGUST W. KURZ, a citizen of the United States, and a resident of Cleveland, in the county of Cuyahoga and State of Ohio, have invented certain new and useful Improvements in Catch-Basin Receiving-Heads, which improvements are fully set forth in the following specification.

This invention relates to improvements in structures of that class employed in connection with catch-basins or analogous structures, such as manholes or other openings into subterranean vaults, and the same serving to control the entrance thereto.

The object of this invention is to provide a structure of the character indicated which shall be simple and inexpensive as regards construction, durable, efficient, and reliable in practical service, which shall embody elements relatively adjustable to suit conditions involved in the installation of the head for service, together with elements whereby are secured important results in connection with the detachable lid made use of and the latter's application to and removal from the main member of the construction, which shall be attractive in appearance, and which shall possess certain well-defined advantages over prior analogous structures.

The invention consists in the novel disposition and relative arrangement of the various coöperating parts thereof, whereby the attainment of the above object is rendered practicable in certain combinations and in certain details of construction, all of which will be specifically referred to hereinafter and set forth in the appended claims.

The invention is clearly illustrated in the accompanying drawings, wherein similar reference characters denote corresponding parts throughout the several views.

As to said drawings, Figure 1 is a plan view of a catch-basin receiving-head embodying my said improvements. Fig. 2 is a side elevation of said receiving-head. Fig. 3 is a central vertical longitudinal section along the line *aa* of Fig. 1. Fig. 4 is a perspective view of said receiving-head, and to more clearly disclose the operative relation existing

between the manhole of the construction and the detachable lid employed for spanning said manhole in practice said lid is shown as having been displaced from its normal position and arranged obliquely across said manhole. Fig. 5 is a detail view showing automatic lock mechanism employed in connection with the detachable lid of my improved receiving-head, said view being mainly in section on the line *bb* of Fig. 6 and the scale being enlarged. Fig. 6 is a detail elevation of said lock mechanism, the scale conforming to that of Fig. 5. Fig. 7 is a bottom plan view of a detachable lid for said receiving-head, said lid being modified somewhat as to details of construction. Fig. 8 is a side elevation of the inverted lid shown in Fig. 7.

In a general sense my invention comprises an extended main member, a hood adjustably conjoined with said main member, the latter presenting to said hood under all degrees of adjustment thereof relatively to said main member a point of supporting resistance substantially in the same plane with the point of support on the hood.

It further comprises a main member forming a manhole for the construction and a detachable lid for spanning said manhole, said lid being provided with a guard, whereby its passage interiorly of said manhole beyond a prescribed plane is prohibited.

It still further comprises a main member forming a manhole for the construction, a detachable lid for spanning said manhole, and automatically-operating mechanism for locking said lid in position through the adjustment thereof for service at said manhole.

In carrying out my invention, reference being had to the accompanying drawings, I employ a main member 2, forming the manhole for the structure as a whole, said member having a base-flange 2' and being extended rearwardly to receive a hood 2'', said parts, respectively, being readily produced from metal by the process of casting.

The hood 2'' has an intake 3 and is rearwardly extended, substantially as shown, to provide ample sweep for such waste or surface water as may in practice seek the inte-

rior of the basin in connection with which my improved receiving-head may be used, such water primarily entering the hood 2" by way of its intake 3. This rearwardly-extending 5 feature of the hood 2" is particularly advantageous where the chief intake for the waste or surface water aforesigned is provided as an element of said hood.

The hood 2" terminates at its lower portion 10 in a depending lip 3', offset inwardly to nicely escape the vertical adjacent wall of the member 2 when said hood is in position for service. This offsetting of the lip 3' results in the formation of a shoulder 3", preferably co- 15 extensive horizontally with the rear portion and opposite sides of the hood 2", and this applies also to the lip 3', the latter serving, essentially, to close the space intervening between the upper edge of the adjacent portion 20 of the member 2 and the shoulder 3" under certain adjustments of said hood with respect to the member 2. For the purpose of effecting this adjustment of the hood 2 I interpose between the shoulder 3" and the upper edge 25 of the adjacent wall of the member 2 one or more separating segments, strips, or pieces 4, the same being here shown each in the form of a flat block constructed from metal, cement, or other suitable material. I have shown each 30 of the separator-blocks 4 as being dovetailed in place for service, its upper and lower edges being oppositely beveled, and the shoulder 3" and upper adjacent edge of the member 2, respectively, being correspondingly shaped, 35 and where this feature is availed of a distinct fastener in the form of a bolt and nut or otherwise for retaining purposes in connection with said separator is not required.

It will be seen that the separator-blocks 4 40 may be replaced by others varying therefrom in height and that the hood 2" may be accordingly raised or lowered with respect to the member 2; but under each and all degrees of such adjustment of the hood 2" the point of 45 support on said hood is always substantially in line with the line of supporting resistance of the main member no matter what the width or height of the separating-blocks may be. Thus the hood 3 has a firm and, in conjunction 50 with the bolts 5, a rigid bearing at all adjustments on the wall of member 2 itself. By this means all shearing tendency is avoided and the hood given a firm support at all elevations above the base member.

The hood 2" and member 2, with the separator or separators 4 interposed between them, 55 may be rigidly secured together in any appropriate manner, though to this end I have shown said hood and said member as being provided 60 the one with a lateral eye-clip 4' and the other with a like eye-clip 4", said eye-clips 4' 4" being arranged in vertical alinement and through which extends a headed bolt 5, threaded to receive a nut 5', these features of the construction being accordingly arranged so that due

homeward turning of the nut 5' will result in the rigid securing together of the hood 2" and member 2, with the separator or separators 4 between them, as hereinbefore mentioned. It will be understood that the fasteners just described or parts analogous thereto may be duplicated at any desired point or points along the outer or inner side of the hood 2" and member 2, as clearly indicated in Fig. 3 of the drawings.

Interiorly of the member 2, forming the manhole of the general structure, and near the upper extremity of the exposed portion of said manhole there is arranged a seat 5", adapted to receive and support a detachable 80 lid 6, the latter when in position spanning the manhole aforesigned. The lid 6 may be substantially integral, as indicated in Fig. 4 of the drawings, and in this connection the importance of the rearwardly-extending feature 85 of the hood 2" becomes clearly apparent, as in such case practically the entire volume of the waste or surface water to be taken care of must enter the intake 3. Said lid may, however, approximate the character of a grate, as 90 indicated in Fig. 7 of the drawings, and under such conditions the rearwardly-extending feature of the hood 2" is not strictly essential, although desirable, as in the event of an accumulation of waste materials or substances 95 at the grate-like lid aforesigned sufficient to divert the volume of waste or surface water to be cared for, or a substantial portion thereof, into the hood 2" by way of its intake 3.

To the end that the lid 6 may not be passed 100 accidentally or intentionally interiorly along the manhole formed by the member 2 beyond its seat 5", and accordingly into the basin in connection with which the structure as a whole is used, I provide said lid with a guard, (designated as an entirety in the drawings by the character F.) This guard may be formed as a 105 separate attachment, as from segments of angle-iron bolted or otherwise secured together, Fig. 3, and thereafter as a completed attachment secured to the lid 6, as by means of bolts 6", or when preferred the various elements of said guard may be formed integral with the lid 6, Figs. 7 and 8, as by the process of 110 casting. More specifically, said guard comprises a looped member 7, traversing the under side of the lid 6 and projecting rearwardly therefrom, opposing side members 7' 7" depending from said looped member, and a 115 transverse member 8 connecting said side members, the several guard members mentioned being suitably braced, as indicated in the drawings. The guard F serves to materially strengthen the lid 6 in addition to its function of preventing undue passage of said lid inwardly along the manhole of the structure.

If the general contour of the manhole of the structure were such as to conform substantially to a true circle and the lid 6 were 120

shaped accordingly, it would not be a difficult problem to arrange the seat 5" so as to prevent undue inward displacement of said lid, such construction being common and well known; but for manufacturing, commercial, and other substantial reasons it is quite inadvisable to provide a structure of the general character herein described with a manhole and lid therefor of the general contour, respectively, above mentioned. The reverse, however, is true where such structure is provided with a manhole and lid therefor of a general contour, respectively, other than circular. For illustration, if said manhole be of an angular general contour, as indicated in the drawings, or of an elliptical general contour and the lid therefor be accordingly shaped inward displacement of said lid may in the absence of provisions to the contrary, as the guard F, follow certain manipulations of the lid, and such manipulations may be accidental or intentional, as will be readily understood. Accordingly I provide my improved receiving-head with a manhole of a general contour other than circular, and the lid 6 therefor, conforming substantially in contour with the contour of said manhole, I provide it with said guard.

In applying the lid 6 for service its front portion is held somewhat upwardly from the member 2, while its rear portion is eased downwardly to the seat 5", the looped member of the guard F accordingly projecting into the hood 2", whereupon the front portion 35 of the lid is eased downwardly until said lid is brought to a fair seating engagement at proper edges thereof with the seat 5", the depending portion of said guard under such conditions projecting downwardly into the member 2 and the rearward prolongation 7 of the guard F coming against the stop 9" on the hood, as shown in Fig. 3, for a purpose to be described hereinafter. Under any other adjustment of the lid 6 with respect to the manhole of the structure contacts are effected between variable points of the guard F and lid 6, jointly or separately, and like points of the member 2 and hood 2", jointly or separately, thus preventing the passage of lid 6 inwardly 45 into the manhole beyond the seat 5". In this connection 8' is a shouldered latch movable upwardly and downwardly along a plane inclined rearwardly and upwardly from the front of the member 2. The upward movement of said latch is effected under manual effort duly applied and the downward movement thereof is effected by its own gravity. Said latch is suspended from a short shaft 8", which projects at its opposite ends into corresponding rearwardly and upwardly inclined elongated openings formed in the opposite sides of the socket 9, one of said openings being shown in Figs. 5 and 8, and said socket is here shown as formed integral with the lid 6, at the under side thereof, near its front

edge. The latch 8' works in the socket 9, the latter being open at its front to permit due projection of the shouldered portion of said latch therefrom to a point underneath the seat 5" for a locking effect under normal 70 conditions of the parts, as shown in full lines in Figs. 5 and 6. Under the conditions of the parts last named displacement of the lid 6 upwardly or otherwise from its seat 5" becomes impracticable until said latch shall 75 have been properly adjusted as to the position indicated in dotted lines in Fig. 5 and as in opposition to its own gravity.

To accomplish the adjustment of the latch 8' last referred to, any suitable key or implement, hooked or otherwise, duly shaped at one end, may be passed downwardly through the lid 6, Fig. 4, by way of the keyhole 9', formed therein, or downwardly through the grate-like lid 6, Fig. 7, by way of one of the 85 openings formed in the latter, said implement being adapted to permit the application of a lifting force to said latch, as will be clearly understood. Under such upwardly-displacing action of the latch 8' (said latch being accompanied at all times by the shaft 8") its depending portion rides upwardly along the upwardly and rearwardly inclined back of the socket 9, by which said latch is held in position under normal conditions, so that its 95 shouldered portion takes under the seat 5" for a locking effect, as herein stated.

It will be seen that as the projecting loop 7 when the lid is in position bears under and against the stop 9" on the rear inside face of 100 the hood that end of the lid is prevented from tilting up, thus acting in conjunction with the lock to prevent any raising of the lid after it is in position on the manhole, as clearly shown in Fig. 3.

The operation of my improved receiving-head will be apparent from the foregoing description thereof, and it will be seen that the construction herein set forth may be modified to some extent without materially departing 110 from the spirit and principle of my invention.

While my invention is particularly adapted to catch-basin heads, yet it is suitable for use with other forms of manholes or for use with any vault or conduit having an opening therein. 115

Having fully described my invention, what I claim, and desire to secure by Letters Patent, is—

1. A catch-basin receiving-head comprising a main member; a hood conjoined with said member, said hood having a shoulder and a lip depending from said shoulder; one or more separator-blocks between the shoulder of said hood and the adjacent portion of said member; and means for holding said hood with the separator-blocks aforesigned in position as stated, rigidly in conjunction with said main member, substantially as described. 120

2. A lid for catch-basin receiving-heads of a contour other than circular, having a down- 125

wardly-projecting guard on its under side for preventing sidewise or endwise passage of the lid through the receiving-head, substantially as described.

5 3. A lid for catch-basin receiving-heads of a contour other than circular, having a downwardly-projecting detachable guard on its under side, for preventing sidewise or endwise passage of the lid through the receiving-head, 50 substantially as described.

10 4. In a receiving-head for catch-basins having a manhole-opening of a contour other than circular, and lid-seats therein, a lid adapted to normally rest on said seats, and a downwardly-projecting guard on its under side for preventing the insertion of the lid into the manhole beyond said seats, substantially as described.

15 5. In a receiving-head for catch-basins having a manhole-opening, a lid for partly spanning said manhole-opening, and a hood covering the remainder of said manhole-opening and having a side opening, the said lid having a perforated lateral extension projecting, 60 when the lid is in its normal position, into said hood by way of its side opening, and preventing passage of the lid through the manhole aforesaid, substantially as described.

20 6. In a receiving-head for catch-basins having a manhole-opening, a lid for partly closing said manhole, a hood covering the remainder of said manhole and having a side opening, and a lateral extension on said lid projecting into said opening of the hood when the lid is 65 in place, and preventing passage of the lid through the manhole, substantially as described.

25 7. In a receiving-head for catch-basins having a manhole-opening, the combination with 70 a lid for closing the same, of a guard projecting downwardly from the lid, and a guard projecting laterally from the lid, both guards together serving to prevent passage of said lid endwise or sidewise through said manhole, 75 substantially as described.

30 8. In a receiving-head for catch-basins hav-

ing a manhole-opening, and longitudinal seats for a lid in the opening, a lid adapted to normally rest on said seats and close said opening, a downwardly-projecting guard on the under side of said lid and a guard extending laterally from said lid, both guards combined preventing passage of the lid beyond the seats, substantially as described.

35 9. In a receiving-head for catch-basins having a manhole-opening, a lid for partly closing said manhole-opening, a hood having a side opening for covering the remainder of said manhole-opening, a lateral guard on and projecting beyond said lid, extending into said opening of the hood when the lid is in place, 60 and a downwardly-projecting guard on the under side of said lid, the said guards preventing sidewise or endwise passage of the lid through the manhole, substantially as described.

40 10. In a receiving-head for catch-basins, having an opening therein, a lid for partly covering said opening, and a hood above the uncovered part of said opening having an interior projection; one end of said cover being 70 provided with a guard for taking under said projection, and the opposite end having a gravity-lock engaging with the side of the receiving-head, substantially as described.

45 11. The combination in a catch-basin receiving-head having a manhole-opening of a contour other than circular, of a hood having a side opening, and a lid for the receiving-head, the said lid extending into said hood by way of the latter's side opening, substantially as 80 herein specified.

50 12. The combination in a receiving-head for catch-basins, of a hood having a side opening therein, and a lid for the receiving-head extending into the opening of said hood, substantially as described.

AUGUST W. KURZ.
